UNITED STATES PATENT OFFICE

JOHN W. MOORE, OF DETROIT, MICHIGAN, ASSIGNOR TO THE AUTOFONT COMPANY, OF DETROIT, MICHIGAN, A CORPORATION OF MICHIGAN

DISPENSING APPARATUS

Application filed March 8, 1930, Serial No. 434,249. Renewed June 9, 1932.

My invention relates to dispensing apparatus, and particularly to a dispensing device rendered operative by the insertion of a proper coin to dispense a gas-charged beverage, such as ginger ale.

The general object of the invention is to produce a simple, inexpensively manufactured, reliable and efficient device which, after insertion of a proper coin and turning of a lever by the purchaser, operates to dispense a drinking cup and deliver a charge of beverage thereto, with the pressure of the beverage assisting in automatically controlling the various steps of the measuring and dispensing operation and restoration of the operating parts to normal position after a dispensing operation.

The various features of construction, arrangement and operation of my invention are incorporated in the structure on the drawings, in which drawings:

Figure 1 is a front elevation of the device with the cover removed to show the dispensing controlling apparatus;

Figure 2 is a rear elevation of the dispensing apparatus supporting panel, showing particularly the measuring element and the valve mechanism for controlling the flow;

Figure 3 is a front elevation of the cover of the device, showing the arrangement of the coin insertion and coin return openings and the lever by means of which the dispensing device is set in operation;

Figure 4 is a rear elevation of the cover, showing the coin-controlled elements for cooperating with the dispensing mechanism shown in Figure 1, and

Figure 5 is a side elevation of the cover and parts supported thereon.

Describing first the coin-receiving and controlled mechanism shown in Figures 3, 4 and 5, the cover panel 1 has the coin inlet 2, which, in this case, is intended for the reception of nickels. Below this coin inlet the panel journals a shaft 3 having at its outer end the main operating lever or handle 4 which is turned in clockwise direction by the purchaser after he has inserted a nickel in the coin inlet. Secured on the inner side of the panel is the coin chute 5 which extends be-

tween the inner end of the coin inlet and the coin-receiving disc 6 secured to the inner end of the shaft 3. The disc has the radially extending coin-receiving slot or pocket 7 which is normally below and in register with the outlet end of the coin chute, so that, if a proper coin C is inserted, it will pass down the chute and be deposited in the pocket.

The disc 6 has a stop notch 8 in which the end of a pawl 9, pivoted at 10, is normally held by means of a spring 11, this pawl serving to prevent turning of the shaft 3 in counterclockwise direction by the purchaser.

A spring 12 is anchored at one end to a post 13 and at its other end is secured to the disc 6 by means of the post 14, the spring, intermediate its ends, having convolutions 15 which surround the hub 16 extending from the panel 1 and journaling to shaft 3. The spring tends to hold the disc 6 in normal position with its notch 8 receiving the pawl 9 and with its coin pocket 7 below the coin chute, as shown in Figure 4.

A cylindrical post or roller 17 on the disc 6 is adapted, when the disc is turned in clockwise direction by the turning of the handle 4 by the purchaser, to engage with the dispensing controlling mechanism in a manner to be hereinafter more fully described.

A detent pawl 18 is pivoted at its outer end on a post 19 extending from the panel 1 and has its inner end shaped to fit in the coin pocket 7 when the disc 6 is turned in clockwise direction and when there is no coin in the pocket. A spring 20 holds the pawl to the disc and normally with its end against the cylindrical surface of the disc just in advance of the coin pocket. If a proper coin has been inserted, it will pass through the chute and drop into the coin pocket 7 and then, upon rotation of the disc by the purchaser, the coin will engage with the pawl 18 and prevent the pawl from dropping into the pocket, and the disc can then be rotated a sufficient distance to carry the pocket around so that the coin may drop therefrom by gravity, and also a sufficient distance to cause effective operation of the dispensing mechanism by the engagement therewith of the post or roller 17. However, if a coin has

not been received by the coin pocket and attempt is made to turn the disc by means of the handle 4, the disc will rotate only a short distance until the pawl 18 is received in the 5 empty coin pocket, as the abutting engagement of the disc with the pawl will then prevent further rotation and, consequently, the machine dispensing mechanism will not be operated.

10 After an operation of the lever 4 in clockwise direction and then release thereof, the spring 12 will restore the disc 6 to normal position with its notch 8 receiving the stop pawl 9. Thus, the lever 4 cannot be turned 15 in counterclockwise direction, and can be turned only a short, ineffective distance in clockwise direction if a proper coin has not been inserted into the machine.

18 A magnet 21 is provided to deflect magnetic coins or tokens from the main chute into a return chute 22 which discharges the false coin or token into the cup 23 on the machine cover. The chute 5 also has an outlet 24 for coins smaller than nickels, which coins, 25 upon reaching this opening, will be deflected by a spring 25 and will drop to the bottom of the machine housing.

Referring now to Figure 1, the dispensing controlling apparatus is mounted behind the 30 cover panel 1 on a panel 26 supported on a plate or frame 27. Mounted on the panel 26 is a base plate 28 from which rises a stop post 29 from whose upper end extends the arm 30 terminating in a hub 31. Between the base 35 and the arm is an actuating disc 32 which is rigidly secured on a shaft 33, which shaft is in axial alinement with the shaft 3 and is journaled in the hub 31 and the base plate carries at its outer end a lever 34 which is in 40 the path of the post or roller 17 on the disc 6 which is turned by the prospective purchaser when he turns the shaft 3 by means of the lever 4. The disc 32 has spaced apart stop arms 35 and 36 for abutting against the post 45 29 in different positions of the disc. A spring 37 is anchored at one end on the stop post 29 and its other end is secured to the lever 34, the spring, intermediate its ends, having convolutions 39 surrounding the shaft 33, the 50 spring tending to hold the disc 32 with its stop 35 against the post 29 and to resist rotation of the disc in clockwise direction when the lever 4 is turned by the purchaser.

55 Fulcrumed on the shaft 33 to swing thereon and extending upwardly therefrom is the actuating lever 40 which is held in normal position by a tension spring 41 anchored to a post 42 extending from the panel 26. Pivoted on the lever 40 by a pin 43 is a latch arm 60 44 held in normal position by a spring 45 anchored to the lever 40. A laterally extending abutment lug 44' on the trip arm is in the path of a bracket 46 extending upwardly from the disc 32, so that, when the disc is turned, this bracket will engage with

the abutment lug 44' to cause the lever 40 to swing with the disc, the spring 45 holding the lug 44' in abutting position relative to the bracket during such rotation of the disc and the lever therewith. Adjustably mounted on the base or supporting member 28 is a trip plate 47 which is engaged by the latch arm 44 just before the stop arm 36 on the disc 32 encounters the stop post 29 and further rotation of the disc and the lever 40 is stopped. 70 Engagement of the trip arm 44 with the trip plate 47 causes the arm to swing sufficiently to withdraw the stop lug 44' from the bracket 46, so that the spring 41 will then be free to swing the lever 40 back to its normal position. As before explained, rotation of the disc 32 is caused when the prospective purchaser turns the lever 4 and thereby turns the disc 6 whose post 17 engages the lever 34 secured to the disc 32. When the purchaser releases the lever 4, the discs 6 and 32 are returned to normal position by the springs 12 and 37, respectively, the disc 6 then abutting against the stop pawl 9 and the disc 32 being held by the abutment of its arm 35 80 against the stop post 29.

85 Actuation of the lever 40 controls the operation of mechanism for dispensing a drinking cup and also actuates mechanism for controlling the discharge of beverage 90 into the dispensed cup. Within a housing 48 secured to the side of the supporting panel or frame 27 is a cup dispenser 49 for dispensing drinking cups from a stack 50. The dispenser may be of well-known design and forms no part of this invention. It has suitable escapement mechanism (not shown) from which extends a lever 51, which, when swung laterally, operates the escapement mechanism for the one-by-one dispensing of 95 cups from the stack 50, a dispensed cup dropping from the dispenser to rest on the floor 52 of the housing 48 in position to receive a charge of beverage. The dispensing lever 51 is connected with the actuating lever 40 by an adjustable rod or link 53, so that, when the lever 40 is swung its full distance, the escapement mechanism of the dispenser will be 100 actuated and a cup discharged from the 105 dispenser.

110 Describing now the beverage dispensing apparatus, a bell-crank lever 54 is secured to the front end of a shaft 55 which is journaled in the panel 26 and the frame 27 and at its rear end terminates in a head 56 within the frame 57 which forms a measuring chamber or space 58, the frame 57 being secured against the rear side of the frame 27.

115 The vertical end of the bell-crank lever 54 has a pin 59 on its lower end engaging in a longitudinal slot 60 at the upper end of a lever 61 pivoted intermediate its ends on a stud 62 extending from the panel 26. A pin 62' extending from the lower end of the lever 61 pivotally receives the head 63 at the upper 120 125 130

end of a rod 64 which extends through an opening 65 in a bracket 66 extending from the panel 26. Between the bracket 66 and the head 63, a compression spring 67 encircles 5 the rod 64 for resisting rotation of the lever 61. Stop-pins 68 and 69 extending from the panel 26 limit the rotation of the lever 61 to either side of a neutral line extending through the axis of the pivot stud 62 and the opening 65. After the lever has been rotated 10 through this neutral line position the compressed spring 67 will tend to rapidly rotate it the remainder of its movement into engagement with either of the stop posts.

15 The vertical leg of the bell-crank lever 54 has a lateral extension or bracket 70 having the hole 71 therethrough, through which extends a rod or link 72 which at its inner end is connected with the actuating lever 40 by a pin 72' and which at its outer end has the abutment 73 for engaging the bracket 70. This abutment may be a nut threaded to the end of the rod so that it is adjustable. With this arrangement, when the lever 40 is swung 20 as the prospective purchaser turns the lever 4, the abutment 73 will encounter the bracket 70 and the bell-crank lever 54 will be rotated. When the bell-crank lever rotates, its pin 59 engages and rotates the lever 61, and, as soon 25 as this lever has been rotated through the neutral line hereinbefore referred to, the compression spring 67 will rapidly complete the rotation of the lever and of the bell-crank independently of the link 72.

30 Referring to Figure 1, clockwise rotation of the lever 40 will result in counterclockwise rotation of the bell-crank lever, and the lever comes to rest as soon as the lever 61 is stopped by its engagement with the stop post 68.

35 Referring to Figure 2, the frame 57 has an inlet passage 74 connected with a pipe 75 with which is connected a tank (not shown) containing the beverage, such as ginger ale, to be dispensed. The inlet 74 is connected with the measuring chamber 58 by a port 76 which is controlled by a ball valve 77 located in the passageway 74. A stem 78 extending from the valve 77 is guided in posts 79 and 80 on the frame 57 and, at its inner end, is adapted 40 to be engaged by the arm 81 extending from the head 56 secured to the inner end of the shaft 55 to which the bell-crank lever 54 is secured. Between the guide posts 79 and 80, a spring 82 encircles the stem 78 with its lower end abutting against a pin 83 on the rod and its upper end abutting against the guide post 80, the spring resisting upward movement of the stem 78 by the arm 81.

45 The frame 57 has a boss 84 providing the outlet passage 85 for the chamber 58. A plug 85 threadedly engages in the boss 84 and provides at its inner end a seat for the ball valve 86. A link 87 extends from the ball valve through a passage 88 in the arm 89 extending 50 from the head 56 in a radial direction oppo-

site to that in which the arm 81 extends. A tension spring 90 within the passage 85 is connected with the plug end and with the valve 86 and tends to hold the valve on its seat to close flow through the outlet passageway 70.

75 The plug 85 is open to the flow of beverage therethrough, and communicates with a pipe 91 which terminates in a spout projecting into the housing 48 below the dispenser 49 in position to charge beverage into a cup which has been dispensed from the dispenser and which will be supported on the floor 52 of the housing.

80 Normally, as shown on the drawings, the arms 81 and 89 on the head 56 of the shaft 55 are in such position that the arm 81 permits the spring 82 to hold the valve stem 78 to apply the valve 77 to its seat to close the inlet port 76, and the arm 89, by its engagement with the head 87' of the link 87 will hold the valve 86 off its seat against the pull of the spring 90, so that the outlet from the chamber 58 is open. When the bell-crank lever 54 is rotated as a result of rotation of the lever 4 by the prospective purchaser, the shaft 55, and, consequently, its head 56, are rotated (counterclockwise, Figure 1 and clockwise, Figure 2), and such rotation causes the arm 81 to shift the valve stem 78 upwardly to unseat the valve 77, and causes the arm 89 to release the tension on the link 87 so that the spring 90 may move the ball 86 to engage its seat. The inlet to the measuring chamber 58 is then opened and the outlet therefrom is closed, and a supply of beverage flows from the supply tank into the measuring chamber. 95

100 The quantity of beverage delivered to the measuring chamber 58 is under control of the pressure to which the liquid is subjected. Mounted on a bracket 93 which is supported from the panel 26 is a pressure bellows 94 which is connected by a pipe 95 with the measuring chamber 58 near the top thereof. Above the head of the bellows extends a lever 96 105 which is hinged at one end to the bracket 93 and which carries an abutment 97 intermediate its ends for engagement by the bellows head as the bellows is expanded. The other end of the lever 96 carries a swiveled guide and abutment lug 98 through which a rod 99 is slidable, this rod at its lower end being connected with the outer end of the horizontal member of the bell-crank lever 54, the rod at its upper end having an abutment 110 head 100. A tension spring 101 is connected between the panel 26 and the lever 96 and tends to hold the lever in lowered position.

115 When the main operating lever 4 is turned the full distance by the purchaser, the bell-crank lever 54 will assume its lower position, and in this position head 100 on the rod 99 will be in engagement with or just above the abutment lug 98 on the lever 96. As has 120 already been explained, rotation of the bell-

crank lever will result in opening of the measuring chamber inlet by the valve 77 and closing of its outlet by the valve 86.

The liquid under pressure enters the measuring chamber, and the air or gas within the measuring chamber is gradually compressed and flows through the pipe 95 to the pressure bellows to cause expansion thereof. As the bellows expands, its head encounters the abutment 97, and the lever 96 is swung upwardly, its abutment 98 acting against the head 100 of the rod 99, raising this rod and causing initial rotational movement of the bell-crank lever 54 in the reverse direction (clockwise, Figure 1 and counterclockwise, Figure 2). As soon as the bell-crank lever has been thus rotated a distance sufficient to swing the lever 61 through its neutral or dead line, the compression spring 67 will then become effective to rapidly swing the levers 61 and 54 to the ends of their movements. Such rotation of the bell-crank lever, transmitted through the shaft 55, will result in release of the valve 77 from the arm 81 and unseating of the valve 86 by the arm 89. The measuring chamber is thus disconnected from the supply tank and is connected with the spout 92 so that the measured quantity of beverage in the measuring chamber may flow from the spout into the cup dispensed from the cup dispenser. During such outflow of the beverage from the measuring chamber, the pressure is withdrawn from the pressure bellows which is then collapsed by the force of gravity aided by the pull of the spring 101, and all the parts of the machine are now in their normal positions.

Briefly summing up the operation, the prospective purchaser inserts a proper coin in the coin inlet, the coin dropping into the pocket 7 of the disc 6. The purchaser then turns the lever 4 clockwise the full distance, whereby, through the engagement of the post 17 with the lever 34, the disc 32 is rotated, which, by engagement of its bracket 46 with the abutment post 44' on the latch arm, carries with it the actuating lever 40. Through the connecting link 53, the dispenser 49 is operated to drop a cup into position below the spout 92, and, by means of the link 72, and, eventually, by the force of the spring 67, the bell-crank lever 54 is swung to its extreme position with the lever 61 abutting against the stop 68. This movement of the bell-crank lever results in opening of the measuring chamber inlet by the valve 77 and closing of its outlet by the valve 86, and also results in downward movement of the rod 99 to bring its head 100 to the abutment lug 98 on the lever 96. The pressure bellows is now subjected to pressure and expands to swing the lever 96 upwardly and to draw the rod 99 upwardly to cause initial swing of the bell-crank lever 54 in reverse direction, the final movement in such reverse direction

being accelerated by the pressure of the spring 67. At the end of such reverse movement the measuring chamber inlet will be closed and its outlet opened for the discharge of the measured quantity of beverage from the spout 92 into the dispensed cup. If desired, a door 102 may be provided for the housing 48 which the prospective purchaser, after having deposited the coin and turned the lever 4, opens, so that he may withdraw the filled cup.

After discharge of the measuring cup contents, the pressure bellows is relieved and collapses into normal position ready for the next operation of the machine.

Referring to Figure 1, it will be noted that the abutment 73 is normally displaced from the bell-crank lever 54 so that this lever will not be rotated until the lever 40 has been swung a certain distance when the prospective purchaser rotates the handle 4. The adjustment of the abutment 73, and the adjustment of the trip plate 47 for the latch arm 44 are such that, unless the prospective purchaser rotates the lever 4 the full distance in clockwise direction, there will be insufficient movement of the dispensing mechanism to dispense a cup from the dispenser 49 and also insufficient initial movement of the bell-crank 54 to swing the lever 61 through its neutral or dead line, so that, upon release of the lever 4 after only a partial rotation thereof, the dispensing machine parts will merely return to their normal positions without having accomplished any dispensation either of a cup or of beverage.

Holding of the operating lever 4 after turning it the full distance will not interfere with the dispensing operation of the machine as the latch 44, upon engagement with the trip plate 47 at the end of rotational movement of the lever 4, will release the lever 40 so that the spring 41 may return the lever and the link 72 to normal position in order that the bell-crank lever may be restored to normal position by the operation of the pressure bellows.

As compared with other dispensing machines on the market, my improved machine comprises a comparatively small number of parts, and such parts are of simple design and economical to manufacture. The various operating parts cooperate to insure efficient and accurate operation and the dispensing at all times of an accurately measured quantity of beverage to fill the dispensed cup but without overflowing thereof.

Although I have shown one embodiment of the various features of my invention, it is to be understood that changes and modifications may be made without departing from the spirit and principles of the invention, and I, therefore, do not desire to be limited except as is specified in the appended claims.

I claim as follows:

1. In a dispensing machine of the class described, the combination of a measuring chamber having an inlet adapted for connection with a supply source of beverage under pressure and having a discharge outlet, valve mechanism for controlling said inlet and outlet, a setting lever for controlling the setting of said valve mechanism, said valve mechanism in one position of said lever being set to close said inlet and open said outlet and in another position of said lever being set to open said inlet and close said outlet, a main operating lever, a connecting train operated by rotation of said main operating lever to cause movement of said valve mechanism setting lever to set said valve mechanism to close said discharge outlet and open the supply inlet for a charge of beverage into said measuring chamber, and a pressure bellows controlled by the pressure within said measuring chamber to move said valve setting controlling lever for the setting of said valve mechanism to close said supply inlet and open the discharge outlet. 70
2. In a dispensing machine of the class described, the combination of a measuring chamber having a supply inlet and a discharge outlet, said supply inlet being adapted for connection with a source of supply of beverage under pressure, a discharge spout connected with said outlet, valve mechanism for said inlet and outlet, a setting lever connected with said valve mechanism to cause setting thereof for closing of said inlet and opening of the outlet or for opening of the inlet and closing of the outlet, spring-actuated means operable after an initial movement of said setting lever in one direction to complete such movement, a main operating lever rotatable by a prospective purchaser of the beverage to be dispensed, means whereby rotation of said main lever will cause initial movement of said setting lever for subsequent actuation by said spring-actuated means to set said valve mechanism to open said inlet and close said discharge outlet whereby said measuring chamber will receive a charge of beverage to be dispensed, and a pressure bellows controlled by the pressure in said measuring chamber to institute an initial return movement of said setting lever for final movement thereof by said spring-actuated means to cause resetting of said valve mechanism to close said supply inlet and open the discharge outlet for the discharge of the measuring chamber contents from said spout. 80
3. In a dispensing device of the class described, the combination of a measuring chamber having a supply inlet adapted for connection with a source of supply of beverage under pressure and having a discharge outlet, valve mechanism for controlling said inlet and outlet, setting mechanism for said valve mechanism, spring-actuated means operable after initial movement of said setting mechanism in either direction to complete the setting movement thereof, an operating lever, means set in operation by the rotation of said operating lever to cause initial movement of said setting mechanism for final movement thereof by said spring-actuated means to cause setting of said valve mechanism to open said supply inlet and close said discharge outlet whereby said measuring chamber may receive a charge of beverage to be dispensed, and a pressure bellows responsive to the pressure in said chamber to institute initial movement of said setting mechanism in return direction for final return movement thereof by said spring-actuated means to cause resetting of said valve mechanism to close said supply inlet and open said discharge outlet for the discharge of the measured beverage from said measuring chamber. 90
4. In a dispensing device of the class described, the combination of a measuring chamber having a supply inlet for connection with a source of supply of liquid under pressure and having a discharge outlet, valve mechanism for controlling said inlet and outlet, setting mechanism for said valve mechanism, a main operating lever, means rendered effective by operation of said main operating lever to move said setting mechanism to set said valve mechanism to open said inlet and close said outlet, and a pressure bellows con- 100
5. In a dispensing device of the class described, the combination of a measuring chamber having a supply inlet for connection with a source of supply of liquid under pressure and having a discharge outlet, valve mechanism for controlling said inlet and outlet, setting mechanism for said valve mechanism, a main operating lever, means rendered effective by operation of said main operating lever to move said setting mechanism to set said valve mechanism to open said inlet and close said outlet, and a pressure bellows con- 110
6. In a dispensing machine of the class described, the combination of a measuring chamber having a supply inlet and a discharge outlet, said supply inlet being adapted for connection with a source of supply of beverage under pressure, a discharge spout connected with said outlet, valve mechanism for said inlet and outlet, a setting lever connected with said valve mechanism to cause setting thereof for closing of said inlet and opening of the outlet or for opening of the inlet and closing of the outlet, spring-actuated means operable after an initial movement of said setting lever in one direction to complete such movement, a main operating lever rotatable by a prospective purchaser of the beverage to be dispensed, means whereby rotation of said main lever will cause initial movement of said setting lever for subsequent actuation by said spring-actuated means to set said valve mechanism to open said inlet and close said discharge outlet whereby said measuring chamber will receive a charge of beverage to be dispensed, and a pressure bellows controlled by the pressure in said measuring chamber to institute an initial return movement of said setting lever for final movement thereof by said spring-actuated means to cause resetting of said valve mechanism to close said supply inlet and open the discharge outlet for the discharge of the measuring chamber contents from said spout. 120
7. In a dispensing machine of the class described, the combination of a measuring chamber having a supply inlet and a discharge outlet, said supply inlet being adapted for connection with a source of supply of beverage under pressure, a discharge spout connected with said outlet, valve mechanism for said inlet and outlet, a setting lever connected with said valve mechanism to cause setting thereof for closing of said inlet and opening of the outlet or for opening of the inlet and closing of the outlet, spring-actuated means operable after an initial movement of said setting lever in one direction to complete such movement, a main operating lever rotatable by a prospective purchaser of the beverage to be dispensed, means whereby rotation of said main lever will cause initial movement of said setting lever for subsequent actuation by said spring-actuated means to set said valve mechanism to open said inlet and close said discharge outlet whereby said measuring chamber will receive a charge of beverage to be dispensed, and a pressure bellows controlled by the pressure in said measuring chamber to institute an initial return movement of said setting lever for final movement thereof by said spring-actuated means to cause resetting of said valve mechanism to close said supply inlet and open the discharge outlet for the discharge of the measuring chamber contents from said spout. 130

trolled by the pressure in said measuring chamber to actuate said setting mechanism to reset said valve mechanism to close said inlet and open the discharge outlet.

- 5 6. In a dispensing device of the class described, the combination of a measuring chamber having a supply inlet for connection with a source of supply of liquid under pressure and having a discharge outlet, valve mechanism for controlling said inlet and outlet, setting mechanism for said valve mechanism, a main operating lever, a rotational member, means for transmitting the rotation of said main operating lever to said rotational member, an actuating lever rotatable independently of said rotational member, a connection between said actuating lever and said setting mechanism, latch means connecting said rotational member with said actuating lever when said main operating lever is rotated whereby said setting mechanism will be operated to cause setting of the valve mechanism to open said supply inlet and close said discharge outlet, tripping means for tripping said latch mechanism after a predetermined distance of rotation of said actuating lever with said rotational member whereby said actuating lever is released, means for returning the released actuating lever to a position of disconnection from said setting mechanism, and means controlled by the pressure in said measuring chamber for actuating said setting mechanism to reset said valve mechanism to close said supply inlet and open said discharge outlet.

7. In a dispensing device of the class described, the combination of a measuring chamber having a supply inlet for liquid under pressure and having a discharge outlet, valve mechanism for controlling said inlet and outlet, setting mechanism adapted when moved to one position to set said valve mechanism to close said inlet and open said outlet and when moved to another position to open said inlet and close said outlet, a main operating lever, a rotational member, means for connecting said rotational member to rotate with said main operating lever, an actuating lever rotatable independently of said rotational member, yielding means for resisting rotation of said actuating lever, latch means connecting said actuating lever to rotate with the rotational member, when said main operating lever is turned, a connection between said actuating lever and setting mechanism for causing movement of said setting mechanism to one of its positions when said actuating lever is rotated, tripping means operable after a predetermined distance of rotation of said rotational member to actuate said latch mechanism to release said actuating lever from said rotational member, means permitting return of the released actuating lever to normal position without disturbing the setting of said setting mechanism, and means

controlled by the pressure in said measuring chamber for returning said setting mechanism to normal position.

8. In a dispensing device of the class described, the combination of a liquid measuring chamber having an inlet for liquid under pressure and having a discharge outlet, valve mechanism for controlling said inlet and outlet, setting mechanism for said valve mechanism, spring-actuated means adapted after an initial movement of said setting mechanism in either direction to rapidly complete such movement, a rotational member and means for rotating it, an actuating lever rotatable independently of said rotational member, a spring resisting rotation of said actuating lever, latch means for latching said actuating lever to rotate with said rotating member when said member is rotated, a connection between said actuating lever and said setting mechanism for effecting initial movement of said setting mechanism when said actuating lever is rotated whereby said spring-actuated means will become effective to complete the movement of said setting mechanism, means for actuating said latch mechanism to release said actuating lever for return to normal position after actuation of the setting mechanism, and means responsive to the pressure in said supply chamber for effecting initial movement of said setting mechanism in reverse direction for final movement in such direction by said spring-actuated means.

9. In a dispensing device of the class described, the combination of a liquid measuring chamber having an inlet for liquid under pressure and having a discharge outlet, a shaft extending into said chamber, a valve for said inlet and a valve for said outlet, arms on said shaft, interconnecting mechanisms between said arms and said valves operable upon rotation of said shaft in one direction to close one of said valves and open the other and to effect reverse movement of said valves when the shaft is rotated in the opposite direction, a lever on said shaft, manually controllable means for effecting swing of said lever to rotate said shaft in one direction, and means controlled by the pressure in said chamber for swinging said lever in the opposite direction.

10. In a dispensing device of the class described, the combination of a liquid measuring chamber having an inlet for liquid under pressure and having a discharge outlet, a valve for said inlet and a valve for said outlet, a rotatable member within said chamber, connections between said rotatable member and said valves adapted on rotation of said member in one direction to control the movement of said valves to open said inlet and close said outlet and adapted upon reverse rotation of said member to control said valves to close said inlet and open said outlet, an actuating

- lever for said rotatable member, spring-actuated means adapted upon initial movement of said lever in either direction a rapidly complete such movement, manually controllable
5 means for effecting initial movement of said lever in one direction, and means controlled by the pressure within said chamber for effecting initial movement of said lever in the reverse direction.
- 10 11. In a dispensing device of the class described, the combination of a liquid measuring chamber having an inlet for liquid under pressure and having a discharge outlet, valve mechanisms for controlling said inlet and
15 outlet, setting mechanisms for said valve mechanisms, a rotational member adapted for manual rotation in one direction, an actuating lever rotatable with said rotational member when manually rotated, a connection be-
20 tween said actuating lever and said setting mechanisms for causing operation of the setting mechanisms during movement of said actuating lever with said rotational member, movement of said setting mechanisms by said
25 lever causing setting of said valve mechanisms for dispensing operation of the device, means for releasing said actuating lever from said rotational member at the end of the manual rotation of said member and for
30 returning it to normal position in which it will not interfere with the return movement of said setting mechanisms, and means controlled by the pressure of the liquid for returning said setting mechanisms to normal
35 position.

In testimony whereof I have hereunto subscribed my name at Detroit, Wayne County, Michigan.

JOHN W. MOORE.
